WHEEL AND AXLE ASSEMBLY

Alfred H. Oelkers and Fred E. Bachman, Chicago,
Ill., assignors to American Steel Foundries,
Chicago, Ill., a corporation of New Jersey

Application March 6, 1933, Serial No. 659,659

23 Claims. (Cl. 308—180)

This invention relates to improvements in wheel and axle assemblies for railway rolling stock and more particularly to the provision of a roller bearing assembly through which the journal box is mounted on the axle.

It is an object of this invention to provide for the installation of a roller bearing in a railway car journal box in such a manner that a certain amount of lateral movement of the journal box assembly on the axle end is permitted and of a construction that permits easy removal of the roller bearing from the journal box without removing the journal box from the car truck and also a construction which permits the replacement of any single part of the assembly without special tools and without removal of the journal box from the car truck.

It is further an object of the present invention to provide improved means through which a roller bearing unit is positioned upon an axle end.

It is further an object of the present invention to provide a resilient support for a journal box upon a roller bearing assembly carried by an axle.

With these and various other objects in view, the invention may consist of certain novel features of construction and operation as will be more fully described and particularly pointed out in the specification, drawings and claims appended hereto.

In the drawings:

Figure 1 is a sectional elevation of a wheel and axle assembly;

Figure 2 is an end elevation of Figure 1 with the left portion of the journal box cover cut away;

Figure 3 is a sectional elevation similar to Figure 1 showing a modified construction;

Figure 4 is an end view of Figure 3 with the left portion of the journal box cover cut away;

Figure 5 is a sectional elevation similar to Figure 3 but illustrating a modified construction of the roller bearing assembly;

Figure 6 is a detail section of a roller bearing assembly showing a modified arrangement; and

Figure 7 is a detail view similar to Figure 6 illustrating a further modification.

In Figure 1 the car axle 20 has fixedly mounted thereon a wheel 22. Adjacent the wheel 22 a deflector ring 24 is mounted on the axle. A reduced portion 26 of the axle extends into the journal box 28. The rear wall 30 of the journal box has an annular portion 32 closely adjacent the cylindrical surface of axle 20. The wall 30 also has a flange 34 overlapping the deflector ring 24. A lubricant deflector ring 35 is provided at the inner

end of the roller bearing assembly. These parts, therefore, serve as sealing means to prevent the loss of lubricant from the journal box and the entrance of dust. The journal box is closed at its outer end by a cover 36 secured by bolts 38.

The axle has a tapered portion 39 upon which is fitted the correspondingly tapered portion of one part 40 of the roller bearing cone. The second part 42 of the roller bearing cone has an annular fit over the part 40 and abuts against a shoulder 41. The part 40 has a convex roller raceway surface 44 and the part 42 has a similar convex surface 46. Two courses of conical rollers 48 and 50 are provided, the rollers being retained by a bearing cup 52 having conical roller-engaging surfaces 54 and 56. The two courses of rollers are held in separated positions by roller cages 58 and 60. The end of the axle is provided with a threaded portion 62 to which is secured a nut 64. The nut 64 serves to force a retainer sleeve 66 having a tapered portion 68 into engagement with a correspondingly tapered portion of the cone part 42. The nut 64 is provided with a retainer 70 on its outer end which has a projection 72 adapted to engage one of a plurality of holes 74 provided at the axle end.

The bearing cup 52 has a limited clearance for shifting laterally with respect to the journal box by the provision of a flange 76 integral with the journal box and an inwardly directed flange 78 on the cover 36. The journal box has a bearing portion 82 extending between points 84 and 86, as indicated in Figure 2.

The large outer ends of the tapered rollers 48 and 50 abut against thrust shoulders 88 and 90 formed at the edges of the bearing cup 52. It will be noted that by the removal of the cover plate 36, the nut 64 is accessible for removal from the axle and that the entire roller bearing assembly may be moved outward from the journal box after the nut 64 has been removed.

In Figure 3 the roller bearing assembly comprises an inner cone 100 and an outer bearing cup 102. The cone 100 has a spherical roller raceway 104 and the bearing cup 102 has a pair of spaced complementary raceways 106. Two courses of concave rollers 108 are employed, retained by separate cages 110. The roller bearing assembly is laterally movable with respect to the journal box between the inner shoulder 76 and outer segmental lock ring 112, seated in a groove of the journal box 28 and retained by fastening bolts 114. The inner bearing cone 100 has a tapered bore 116 at each end. One end of the cone is adapted to seat upon the conical por-

tion 118 of the axle 20 and the other tapered end of the cone 100 is adapted to be engaged by the tapered ends of the two-part retainer sleeve 120. The retainer sleeve parts 120 fit upon the 5 cylindrical portion 122 of the axle and have annular shoulders 124 at their outer ends fitting into an annular groove 126 formed in nut member 128 which is threaded to the axle end. The nut 128 has secured thereto a lock ring 130 having 10 a plurality of notches 132 adapted to be engaged by bolts 134 which thread into the axle end. The bolts 132 are fastened together by a lock wire 136.

The nut 128 is therefore utilized for forcing the 15 two-part sleeve 120 into assembled positions thereby tightening the bearing cone 100 on the axle end. By removing the nut, the sleeve parts 120. The retainer sleeve parts 120 fit upon the cone 100 so that it may be easily slipped from 20 the end of the axle.

Figure 5 illustrates a construction in general similar to that shown in Figure 3 but having a modified roller bearing assembly. The cone 140 is formed similar to the cone 100 in Figure 3 and 25 has a spherical roller raceway 142. Three courses of concave rollers 144, 146 and 148 are employed, the outer courses 144 and 148 running on the complementary surfaces of bearing cup members 150 and 152 while the middle course of rollers run on 30 the central bearing cup element 154. The bearing cup elements are held together by the retainer sleeve 156 flanged over at its edges as at 158. A single roller cage 160 is employed having perforations or apertures for retaining and guiding 35 the three courses of rollers. The cage 160 has inwardly projecting lugs 162 between the rollers forming the middle course, which lugs extend into close proximity to the surface of cone 140 thereby 40 guiding the roller cage to run concentrically in the bearing.

Due to the provision of a single cage for all 45 three courses of rollers, it is necessary that the rollers be of proportionate diameters to the size of the cone diameter around which they rotate and for this reason the diameter of the middle course of rollers 146 is proportionately larger than the diameter of the end rollers 144 and 148. Also the end rollers 144 and 148 are tapered, having 50 smaller diameters at their outer ends than at their inner ends. It will further be noted that the end rollers 144 have conical inner ends 164 adapted to abut the ends of the rollers 146 while the rollers 148 have similar conical inner faces 166 abutting the adjacent ends of the rollers 146.

55 The journal box 28 which rests upon the roller bearing assembly is separated therefrom by a layer of insulating material 168 which may also be of a resilient nature for the purpose of absorbing vibrations and shocks between the weight-carrying journal box and the axle. The roller bearing assembly may be inserted and removed in the same manner as previously described with respect to the form shown in Figure 3.

Figure 6 shows a further modification of the 65 roller bearing assembly comprising a cone 170 having a spherical raceway 172 upon which run three courses of rollers 174, 176 and 178. Each of the rollers has a central portion 180 of concave shape for running on the spherical surface 70 172 while the end portions 182 of the rollers 174 and 178 are conically shaped to engage the complementary surfaces of the bearing cup rings 184 and 186. The end portions of the central course of rollers 176 are cylindrically formed, as shown 75 at 188, for running on the flat surface of the cen-

tral bearing cup ring 190. The bearing cup rings are held in assembled position by the retainer sleeve 192.

The cage of this bearing assembly is a unitary element 194. The ends of the roller cage run in 5 close proximity to the cylindrical surfaces 196 at the outside edges of the rings 184 and 186. The rollers are of such proportionate diameters that they all have the same peripheral speed around the bearing cone during operation. It will be obvious that this roller bearing assembly, the same as in Figures 3 and 5, is self-aligning to compensate for axle deflection.

Figure 7 shows a double roller race bearing and a spherically surfaced cone 200. Two courses of 15 diagonally disposed rollers 202 abut each other at their large ends and run upon the surfaces of cup rings 204. The cup rings 204 are retained by the flanged casing 206. A single unitary cage 208 is employed for positioning the rollers. The rollers are formed similar to the rollers shown in Figure 6 by having concave central portions and conical end portions. The bearing assembly is 20 self-aligning.

In the constructions described the roller bearing unit is mounted upon the axle in an improved manner by employing wedging means acting at the opposite ends of the bearing cone. This arrangement is more desirable than former designs in which the roller bearing is fixed in position by a single wedge forced on the axle by a nut threaded to the axle end. In the construction disclosed the wedging means at both ends of the bearing cone act to produce an even distribution of load upon the surface of the bearing cone.

It is to be understood that we do not wish to be limited to the exact embodiment of the device shown, which is merely by way of illustration and not limitation, as various other forms of the device will of course be apparent to those skilled in the art without departing from the spirit of the invention as ascertained from the scope of the appended claims.

We claim:

1. In a wheel and axle assembly, a rotatable wheeled axle having a journal end, a journal box into which the journal end of said axle extends, a roller bearing unit positioned in said journal box concentric with the journal end of said axle for transmitting the radial load from said journal box to said axle and comprising inner and outer race rings and two roller courses designed to provide self-alignment between said race rings and to transmit axial thrust in either direction from said axle to said journal box, said inner race ring having a tapered bore at each end thereof, said journal end of said axle having a tapered wedge shoulder thereon adapted to engage the tapered bore at one end of said inner race ring, a pair of segmental wedge members adapted to engage the outer end of the tapered bore of said inner race ring and a nut threaded to the journal end of said axle having interlocking engagement with said wedge members for forcing said wedge members longitudinally with respect to said axle to fixedly position the inner race ring of said roller bearing unit upon said axle.

2. In a wheel and axle assembly, a rotatable 70 wheeled axle having a journal end, a journal box into which the journal end of said axle extends, a roller bearing unit positioned in said journal box concentric with the journal end of said axle for transmitting the radial load from said jour-

5   nal box to said axle and comprising inner and outer race rings and two roller courses designed to provide self-alignment between said race rings and to transmit axial thrust in either direction from said axle to said journal box, said inner race ring having a tapered bore at each end thereof, said journal end of said axle having a tapered wedge shoulder thereon adapted to engage the tapered bore at one end of said inner race ring, a pair of segmental wedge members adapted to engage the outer end of the tapered bore of said inner race ring and a nut threaded to the journal end of said axle having interlocking engagement with said wedge members for 10   forcing said wedge members longitudinally with respect to said axle to fixedly position the inner race ring of said roller bearing unit upon said axle, said outer race ring being free to move for a limited amount laterally with respect to said 15   journal box and a segmental metal key removably fastened to said journal box for limiting the displacement of said outer race ring.

displacement of said outer race ring.

3. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone 25 having a tapered bore at each end, said assembly being disposed on said axle whereby the tapered bore at one end of said bearing cone abuts said axle shoulder, wedge means fitting said axle adapted to engage the tapered bore at the outer 30 end of said bearing cone, adjustable means secured to said axle for moving said wedge means with respect to said axle to fixedly position said bearing cone on said axle, said assembly further 35 including an outer bearing cup disposed in supporting relation with the journal box, and stop means on said journal box cooperating with said bearing cup to permit limited relative lateral 40 movement of said assembly and journal box.

4. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly being constructed and arranged to provide for self-alignment upon relative angular movement of said axle and journal box, said assembly including a bearing cone having a tapered bore at each end, said assembly being disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means with respect to said axle to fixedly position said bearing cone on said axle, said assembly further including an outer bearing cup disposed in supporting relation with the journal box, and stop means on said journal box cooperating with said bearing cup to permit limited relative lateral movement of said assembly and journal box.

5. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a tapered bore at each end, said assembly be-

ing disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means with respect to said axle to fixedly position said bearing cone on said axle, said assembly further including an outer bearing cup disposed in supporting relation with the journal box, said assembly being constructed and arranged to provide for self-alignment upon relative angular movement of said axle and journal box. 5 10

6. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a tapered bore at each end, said assembly being disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means with respect to said axle to fixedly position said bearing cone on said axle, said assembly further including an outer bearing cup disposed in supporting relation with the journal box, said journal box having a removable closure member for removal or adjustment of said assembly without removal of said journal box from said axle. 15 20 25 30

7. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a tapered bore at each end, said assembly being disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means with respect to said axle to fixedly position said bearing cone on said axle, said assembly further including an outer bearing cup disposed in supporting relation with the journal box, and stop means on said journal box cooperating with said bearing cup to permit limited relative lateral movement of said assembly and journal box, said journal box having a removable closure member for removal or adjustment of said assembly without removal of said journal box from said axle. 35 40 45 50 55

8. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly being constructed and arranged to provide for self-alignment upon relative angular movement of said axle and journal box, said assembly including a bearing cone having a tapered bore at each end, said assembly being disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means

with respect to said axle to fixedly position said bearing cone on said axle, said assembly further including an outer bearing cup disposed in supporting relation with the journal box, and stop means on said journal box cooperating with said bearing cup to permit limited relative lateral movement of said assembly and journal box, said journal box having a removable closure member for removal or adjustment of said assembly without removal of said journal box from said axle.

9. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a tapered bore at each end, said assembly being disposed on said axle whereby the tapered bore at one end of said bearing cone abuts said axle shoulder, wedge means fitting said axle adapted to engage the tapered bore at the outer end of said bearing cone, adjustable means secured to said axle for moving said wedge means with respect to said axle to fixedly position said bearing cone on said axle, said assembly further including an outer bearing cup disposed in supporting relation with the journal box, and rollers disposed between said cup and cooperating with the surfaces of said parts.

10. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secured to said axle for moving said wedge means with respect to said axle to fixedly position said bearing cone on said axle, said assembly further including an outer bearing cup disposed in supporting relation with the journal box, and rollers disposed between said cup and cooperating with the surfaces of said parts.

11. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secured to said axle for moving said wedge means with respect to said axle to fixedly position said bearing cone on said axle, said assembly further including an outer bearing cup disposed in supporting relation with the journal box, rollers disposed between said cup and cooperating with the surfaces of said parts.

faces of said parts, and stop means on said journal box cooperating with said cup to permit limited relative lateral movement of said assembly and journal box.

12. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly being constructed and arranged to provide for self-alignment upon relative angular movement of said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secured to said axle for moving said wedge means with respect to said axle to fixedly position said bearing cone on said axle, said assembly further including an outer bearing cup disposed in supporting relation with the journal box, and rollers disposed between said cup and cooperating with the surfaces of said parts. 5 10 15 20 25

13. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secured to said axle for moving said wedge means with respect to said axle to fixedly position said bearing cone on said axle, said assembly further including an outer bearing cup disposed in supporting relation with the journal box, rollers disposed between said cup and cooperating with the surfaces of said parts, said journal box having a removable closure member for removal or adjustment of said assembly without removal of said journal box from said axle.

14. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secure to said axle for moving said wedge means with respect to said axle to fixedly position said bearing cone on said axle, said assembly further including an outer bearing cup disposed in supporting relation with the journal box, rollers disposed between said cup and cooperating with the surfaces of said parts, and stop means on said journal box cooperating with said cup to permit limited relative lateral movement of said assembly and jour-

hal box, said journal box having a removable closure member for removal or adjustment of said assembly without removal of said journal box from said axle.

5 15. In a wheel and axle assembly, the combination of a rotatable wheeled axle having an outwardly facing wedge-shaped annular shoulder thereon adjacent one end, a journal box adapted to receive said end of the axle, a roller bearing assembly disposed between said axle and journal box, said assembly including a bearing cone having a part provided with a tapered bore at one end engaging with said axle shoulder, a part mounted on said first-named part and being provided with a tapered bore, said parts having roller cooperating surfaces, wedge means fitting said axle adapted to engage the tapered bore of said last-named part, adjustable means secured to said axle for moving said wedge means with respect to said axle to fixedly position said bearing cone on said axle, said assembly further including an outer bearing cup disposed in supporting relation with the journal box, rollers disposed between said cup and cooperating with the surfaces of said parts, and stop means on said journal box cooperating with said cup to permit limited relative lateral movement of said assembly and journal box, said journal box having a removable closure member for removal or adjustment of said assembly without removal of said journal box from said axle.

10 16. In a roller bearing assembly, the combination of radially spaced race members, a central course of rollers disposed therebetween for carrying radial load, and courses of rollers on each side of said central course for taking lateral thrust, said rollers being disposed in abutting relation, said rollers having an arcuate surface cooperating with a complementary surface on one of said race members and plane surfaces cooperating with complementary surfaces on the other of said race members.

15 17. In a roller bearing assembly, the combination of radially spaced race members, a central course of rollers disposed therebetween for carrying radial load, and courses of rollers on each side of said central course for taking lateral thrust, said rollers being disposed in abutting relation, each of said rollers having a central arcuate surface cooperating with a complementary surface on the inner of said race members and plane surfaces on each side thereof cooperating with complementary surfaces on the outer of said race members.

20 18. In a roller bearing assembly, the combination of radially spaced race members, a central course of rollers disposed therebetween for carrying radial load, and courses of rollers on each side of said central course for taking lateral thrust, each of the rollers of said last-named course having a conical rolling portion in contact with a roller of said central course, said rollers having an arcuate surface cooperating with a complementary surface on one of said race members and plane surfaces cooperating with complementary surfaces on the other of said race members.

25 19. In a roller bearing assembly, the combination of radially spaced race members, a central course of rollers disposed therebetween for carrying

ing radial load, and courses of rollers on each side of said central course for taking lateral thrust, each of the rollers of said last-named course having a conical rolling portion in contact with a roller of said central course, said rollers having an arcuate surface cooperating with a complementary surface on one of said race members and plane surfaces cooperating with complementary surfaces on the other of said race members, and a single cage for said courses of rollers.

30 20. In a roller bearing assembly, the combination of radially spaced race members, a central course of rollers disposed therebetween for carrying radial load, and courses of rollers on each side of said central course for taking lateral thrust, each of the rollers of said last-named courses having rolling contact with a roller of said central course, said rollers having an arcuate surface cooperating with a complementary surface on one of said race members and plane surfaces cooperating with complementary surfaces on the other of said race members, and a single cage for said courses of rollers having the ends thereof in close proximity to one of said race members for guiding said rollers.

35 21. In a roller bearing assembly, the combination of radially spaced race members, a central course of rollers disposed therebetween for carrying radial load, and courses of rollers on each side of said central course for taking lateral thrust, each of the rollers of said last-named course having rolling contact with a roller of said central course, said rollers having an arcuate surface cooperating with a complementary surface on one of said race members and plane surfaces cooperating with complementary surfaces on the other of said race members, and a single cage for said courses of rollers having the ends thereof in close proximity to the outer of said race members for guiding said rollers.

40 22. In a roller bearing assembly, the combination of radially spaced race members, two courses of rollers disposed between said members, the rollers of said courses having abutting end rolling contact, said rollers having an arcuate surface cooperating with a complementary surface on one of said race members and plane surfaces cooperating with complementary surfaces on the other of said race members, and a cage for said courses of rollers, said cage having a central part in close proximity to the inner of said race members and having its ends in close proximity to the outer of said race members.

45 23. In a roller bearing assembly, the combination of radially spaced race members, two courses of rollers disposed between said members, the rollers of said courses having abutting end rolling contact, each of said rollers having a central arcuate surface cooperating with a complementary surface on the inner of said race members and plane surfaces on each side thereof cooperating with complementary surfaces on the outer of said race members, and a cage for said courses of rollers, said cage having a central part in close proximity to the inner of said race members and having its ends in close proximity to the outer of said race members.

CERTIFICATE OF CORRECTION.

Patent No. 2,071,945.

February 23, 1937.

ALFRED H. OELKERS, ET AL.

It is hereby certified that error appears in the printed specification of the above numbered patent requiring correction as follows: Page 2, first column, line 18, strike out the period and words ". The retainer sleeve parts 120 fit upon the" and insert instead are pulled out thereby releasing the bearing; and that the said Letters Patent should be read with this correction therein that the same may conform to the record of the case in the Patent Office.

Signed and sealed this 27th day of April, A. D. 1937.

(Seal)

Leslie Frazer
Acting Commissioner of Patents.
